UNITED STATES PATENT OFFICE

FREDERICK CHARLES BAKER, OF PORTLAND, OREGON

DESIGN FOR A SEMIINDIRECT DIFFUSING BOWL

Application filed September 16, 1930. Serial No. 36,981. Term of patent 7 years.

To all whom it may concern:

Be it known that I, FREDERICK CHARLES BAKER, a citizen of the United States, residing at Portland, county of Multnomah, and State of Oregon, have invented a new, original and ornamental Design for Semiindirect Diffusing Bowl, of which the following is a specification, reference being had to the accompanying drawing, forming a part thereof.

In the drawing:

Fig. 1 shows a side elevation of a semiindirect diffusing bowl embodying my invention;

Fig. 2 is a perspective view looking up at my semi-indirect diffusing bowl as it would appear when suspended from a ceiling;

Fig. 3 is a top plan view of my semi-indirect diffusing bowl; and

Fig. 4 is a bottom plan view of my semi-indirect diffusing bowl.

I claim:

The ornamental design for a semiindirect diffusing bowl as shown.

FREDERICK CHARLES BAKER.
